UNITED STATES PATENT OFFICE.

GEORGE REILLY, OF FRESNO, CALIFORNIA.

TRACK-LINE BUCK.

1,128,257.

Specification of Letters Patent.

Patented Feb. 9, 1915.

Application filed August 18, 1914. Serial No. 858,574.

To all whom it may concern:

Be it known that I, GEORGE REILLY, a citizen of the United States, residing in the city and county of Fresno and State of California, have invented a new and useful Improvement in Track-Line Bucks, of which the following is a specification.

My invention relates to track line bucks for alining rails wherein an inclined arcuate bar, having a shoe slidably mounted thereon, operates in conjunction with an ordinary lifting jack; and the objects of my invention are first, to provide improved means for facilitating the moving or alining of rail road rails; second, to provide a device of the character described that may be easily and readily placed in position or removed; and third, to provide a device of the character described that is simple of construction and operation and one that can be produced cheaply.

I accomplish these several features by means of the device disclosed in the drawings forming a part of the present specification wherein like characters of reference are used to designate similar parts throughout the said specification and drawings and in which—

Figure 1 is a broken sectional view of one rail of a rail road track disclosing the manner in which the inclined arcuate bar is inserted under one of the rails and also the manner in which the lifting jack is applied thereto. Fig. 2 is a view similar to Fig. 1, but wherein the arcuate bar and the rail have been slightly lifted by the jack, the dotted lines indicating the position to which the rail and ties will slide when the same have been lifted clear of the ground. Fig. 3 is a plan view of Fig. 1 disclosing the manner in which the lower end of the arcuate bar is splayed at the lower or outer end thereof in order to increase the bearing surface thereof and thereby provide an efficient bearing for that end of the said arcuate bar. Fig. 4 is a vertical sectional view taken on line X—X of Fig. 1 in the direction indicated by the arrow, disclosing the manner in which the inclined arcuate bar is ribbed or re-inforced, and the manner in which the shoe is slidably mounted thereon.

It is the present practice, in alining rail road tracks, to provide a number of men each having a bar which is inserted under one of the rails or under the ends of a number of ties and the united energy of the men is

applied to the bars and the rail road track forced bodily in the direction of the required position.

By means of the hereinafter described device the track may be moved more quickly and easily with fewer men, and also less excavation is required between the ties.

The numeral 1 is used to designate what I term an inclined arcuate bar, substantially T-shaped in cross section throughout the greater length thereof for purposes of strength and lightness. The bar 1 is provided with a lateral extension 2 which is arranged to be engaged by an ordinary lifting jack 3 which rests on the ground between the ties 4. The lower end of the bar 1 is splayed or extended laterally in both directions as at 5, so as to prevent the bar 1 from tipping sidewise, and has a flange 6 extending across the lower end thereof so that any weight brought to bear upon the lower or splayed end 5 of the bar 1 will cause the said flange 6 to sink into the earth and thereby prevent a longitudinal movement of the said bar 1.

Slidably mounted upon the arcuate portion of the bar 1 is a shoe 7 having a lateral shoulder 8 therein arranged to engage the under side of a rail 9. The shoe 7 has depending sides 10 which engage the sides of the bar 1 so as to prevent a lateral movement of the said shoe 7 relatively to the said bar 1.

The operation is as follows: The ground under the rail 9 and around the ties 4 is removed in the direction in which the track is to be moved. The splayed end 5 of the bar 1 is inserted between the ties 4 and under the rail 9 and the flange 6 of the said splayed end 5 is securely embedded in the earth in order to prevent a longitudinal movement of the bar 1. An ordinary lifting jack 3 is inserted under the lateral extension 2 of the bar 1 with the said jack 3 resting on the earth between the ties 4. The shoe 7 is positioned so that the lateral shoulder 8 thereon is directly under one edge of the rail to be raised, and by means of the lifting jack 3, the arcuate bar 1 is raised until the said lateral shoulder 8 of the said shoe 7 rigidly engages one edge or the under side of one of the rails, as disclosed in Fig. 1 of the drawings. By means of the jack 3 the end of the bar 1 having the lateral extension 2 thereon is further raised until the nearest ends of the ties are

lifted above the pocket in the ground formed by their weight, as disclosed in full lines in Fig. 2 of the drawings. The weight of the rails and track resting on the shoe 7 will cause the said shoe 7 to slide down the arcuate inclined portion of the bar 1 until the ties 4 again rest on the ground. In sliding downward the rails and ties are deflected to the position indicated in dotted lines 10 in Fig. 2 of the drawings. The bar 1 is then lowered by means of the jack 3 and the operation is repeated until the rails and tie are in the desired location.

It is obvious from the foregoing that I 15 have provided improved means for alining rails that is simple of construction and operation, requires fewer men and with which the desired result may be accomplished more easily and quickly.

20 Having thus described my invention what I claim as new and desire to secure by Letters Patent is—

1. A track liner comprising an inclined arcuate bar; and a shoe slidably mounted 25 upon the said bar and arranged to engage the under side of a rail.

2. A track liner comprising an inclined arcuate bar; a shoe slidably mounted upon the said bar and arranged to engage the 30 under side of a rail; and means adapted to prevent the bar from tipping sidewise.

3. A track liner comprising an inclined arcuate bar having a splayed lower end; and a shoe slidably mounted upon the arcuate portion of the bar and arranged to engage the under side of a rail.

4. A track liner comprising an inclined arcuate bar substantially T-shaped in cross section throughout the greater part of the 40 length thereof and having a splayed lower end thereto; and a shoe slidably mounted upon the bar and arranged to engage the lower side of a rail.

5. A track liner comprising an inclined 45 arcuate bar substantially T-shaped in cross

section throughout the greater part of the length thereof and having a lateral extension arranged to be engaged by a lifting jack and a splayed lower end thereto; and a shoe slidably mounted upon the bar and 50 arranged to engage the lower side of a rail.

6. A track liner comprising an inclined arcuate bar substantially T-shaped in cross section throughout the greater part of the length thereof and having a lateral extension 55 adapted to be engaged by a lifting jack and a splayed lower end thereto; and a shoe slidably mounted upon the bar and having a lateral shoulder thereon arranged to engage the lower side of a rail. 60

7. A track liner comprising an inclined arcuate bar substantially T-shaped in cross section throughout the greater part of the length thereof and having a lateral extension adapted to be engaged by a lifting jack 65 and a splayed lower end thereto; a shoe slidably mounted upon the bar and having a lateral shoulder thereon arranged to engage the lower side of a rail; and means arranged to prevent a longitudinal movement 70 of the bar when it is raised.

8. A track liner comprising an inclined arcuate bar substantially T-shaped in cross section throughout the greater length thereof and having a lateral extension arranged 75 to be engaged by a lifting jack on one end and a splayed lower end having a downwardly turned flange on the other end thereof; and a shoe slidably mounted upon the arcuate portion of the bar and having a lateral shoulder thereon arranged to engage the under side of a rail.

In witness whereof I hereunto set my signature in the presence of two subscribing witnesses.

GEORGE REILLY.
